UNITED STATES PATENT OFFICE.

HARRY WEARNE, OF RIXHEIM, GERMANY.

DESIGN FOR WALL-PAPER.

SPECIFICATION forming part of Design No. 31,961, dated December 5, 1899.

Application filed November 11, 1899. Serial No. 736,696. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a plan view of a strip of wall-paper embodying the features of my design.

The leading features of the design consist in the parallel serpentine bars decorated with serpentine floral sprays and the buds between the bars.

The minor features of the design consist in

the alternate plain and barred panels, for which the serpentine bars constitute borders, the barred panels being decorated with rose-buds arranged in transverse and vertical rows, while the plain panels are decorated with a single row of larger buds.

Having thus described my invention, I claim as new and desire to secure by Letters Patent—

The design for wall-paper as herein shown and described.

HARRY WEARNE.
